UNITED STATES PATENT OFFICE.

PAUL SCHOU, OF COPENHAGEN, DENMARK.

VACUUM-COOLER WITH INTERIOR ABSORPTION.

1,285,415.

Specification of Letters Patent. Patented Nov. 19, 1918.

Application filed March 16, 1918. Serial No. 222,904.

To all whom it may concern:

Be it known that I, PAUL SCHOU, of Copenhagen, in the Kingdom of Denmark, have invented certain new and useful Improvements in Vacuum-Coolers with Interior Absorption, of which the following is a full, clear, and exact description.

The present invention refers to that kind of apparatus for household and other use in which cooling or freezing is accomplished by means of evaporation in vacuum by absorption of the vapors.

The principal feature of the invention consists in that the space or spaces in which the absorption of the vapors takes place and the space or spaces intended for cooling or freezing are immediately adjacent to one another in a common retainer and communicate with each other through openings located at different levels.

This affords not only the advantage that, instead of two retainers independent of each other (a freezing-tank by itself and an absorption tank by itself) there is only one single compendious retainer, but also the advantage that the course of the vapors from the place of evaporation to the place of absorption is comparatively very short, thus accelerating the absorption.

The invention is advantageously carried out by arranging flat absorption-chambers disposed in stories, the one above the other, at the side or sides of the freezing-chamber or outside or inside it, so that there is direct access to an absorbing surface in several superadjacent places in the freezing-chamber. Such a vacuum-cooler may be made of ceramic material, for instance, china, and the story-like superadjacent elements that form

the absorption-chambers may be fused together into a unit and also be united with adjacent parts of the walls of the freezing-chamber, so that the said vacuum-cooler with interior absorption, after being fused together, forms one single, air-tight, unit.

The drawing shows, by way of example, one form of construction in vertical section.

The story-like, superadjacent, groove-shaped elements 1, which form the absorption-chambers 2, are ring-shaped and have, on their upper edges, recesses or hollows 3, through which the absorption-spaces communicate with the freezing-chamber 4 surrounded by the elements. Every element has an overflow 5 whose upper edge lies at a dis-

tance above the bottom of the groove corresponding to the desired layer-thickness of the absorption-means, and whose lower edge is situated at about the same distance from the bottom of the subjacent element. In the section-drawing these overflow-pipes are only visible where they belong to the elements with odd numbers, i.e., the first, third, fifth element, etc. The overflow-pipes of the elements with even numbers lie behind the section-plane. Furthermore there may be other passages 6 in the elements which are not accessible for the means of absorption, but through which the absorption chambers are in direct mutual connection.

The pile of elements stands on a bottom 7 with a ring-shaped groove 8 for the waste absorption-means, which can be tapped off through the cock 9, 10 indicated by dotted lines. On the top of the pile is placed a collar 11 with a ground bearing-surface for a lid 12 with plug 13. On the outside of this collar there are disposed (as shown by the dotted lines), firstly, a filling-socket 14 (with plug 15) through which fresh absorbing-means may be poured down into the uppermost element, secondly a socket 16 which communicates with an inner opening 17, and to which a vacuum pump or vacuum-pipe can be connected, so that the freezing-chamber can thereby be exhausted.

The elements 1, the bottom 7, the collar 11, etc. may, as has already been said, be made of ceramic material. When these different parts are put together in the manner indicated above and fused together, there will be produced a homogeneous, strong, unitary, hollow body, which is air-tight and acid-proof.

When the absorption-means has been poured in, and water introduced into the chamber 4, and the latter has then been closed by the lid 12 and exhausted, the water will evaporate and, owing to the loss of heat caused by the evaporation, will soon freeze. After the vacuum has once been produced, it does not need to be kept up by continued pumping, since the vigorous absorption of the vapors in the absorption-chambers with their great absorbing-surfaces closely surrounding the freezing-chamber on all sides, prevents detrimental rises of pressure. The heat which the water loses by evaporation is taken up by the absorbing-means, which in some cases is heated still more by reaction

on the water. In order to prevent the elements 1 from being thereby so heated that the cooling-effect in the chamber 4 is decreased in a perceptible degree, there is disposed, outside of the elements 1, a cooling jacket 18 for a stationary or circulating cooling-means (water).

5 The aforesaid vacuum-cooler with interior absorption can be used in connection with a 10 box, a cupboard, a sideboard, or the like, the interior of which is cooled off by means of a cooling-means present in hollow walls, or the like, in such a way that the cooling-means constantly receives cold from the 15 vacuum-cooler. For this purpose a pipe 20 may be introduced with air-tight joints through the holes 19 in the bottom 7, said pipe 20 communicating with said hollow walls or the like. As the cooling-means here 20 present is heated, it rises in the pipe 20, where it is cooled, so that it flows back in a cold state.

I claim:

25 1. A cooling apparatus comprising an evaporation chamber and an absorption chamber located side by side and communicating with each other through openings located at different levels.

30 2. A cooling apparatus comprising a separating wall provided with openings at different levels, an absorption chamber located on one side of said wall, and an evaporation chamber located on the other side of said wall, and communicating with the first-named chamber through said openings.

35 3. A cooling apparatus comprising a series of superposed annular members formed with channels to retain an absorption medium and with connecting ducts, and a central chamber surrounded by said members

and communicating with the spaces above said channels.

4. A cooling apparatus comprising a series of superposed annular members provided 45 at their inner portions with openings leading to the central chamber surrounded by said members, each member having a channel for the reception of an absorption medium, open to said central chamber through 50 said openings.

5. A cooling apparatus comprising a series of superposed annular members surrounding a central evaporation chamber, each member having a channel for the reception of an 55 absorption medium, and openings leading to the central chamber above the liquid levels of the respective channels.

6. A cooling apparatus comprising a series of superposed annular members surrounding 60 a central evaporation chamber, each member having a channel for the reception of an absorption medium, an overflow to the next channel below, and openings leading to the central chamber above the overflow 65 levels of the respective channels.

7. A cooling apparatus comprising a series of superposed members surrounding a central evaporation chamber, each member having a channel for the reception of an absorption medium, and openings leading to the central chamber above the liquid levels 70 of the respective channels, and a cooling jacket surrounding said annular members.

In testimony that I claim the foregoing as 75 my invention I have signed my name in presence of two subscribing witnesses.

PAUL SCHOU.
